UNITED STATES PATENT OFFICE.

JAMES L. DE VOU, OF WISSAHICKON, PENNSYLVANIA.

PULLEY-BLOCK.

SPECIFICATION forming part of Letters Patent No. 729,024, dated May 26, 1903.

Application filed March 2, 1903. Serial No. 145,739. (No model.)

To all whom it may concern:

Be it known that I, JAMES L. DE VOU, residing at Wissahickon, in the county of Philadelphia and State of Pennsylvania, have invented certain new and useful Improvements in Pulley-Blocks, of which the following is a specification.

This invention relates to that form of pulley-blocks known as "snatch-blocks;" and it is designed to provide an improved construction of convenient operation having increased strength and reduced tendency to distortion without increased weight or cost.

The nature and characteristic features of the improvements will more fully appear by reference to the following description and the accompanying drawings in illustration thereof, of which—

Figure 1 represents a front elevation of a snatch-block made in accordance with my invention. Fig. 2 represents a rear elevation thereof. Fig. 3 represents a vertical transverse sectional view thereof. Fig. 4 represents a front elevation of a modified form of construction, and Fig. 5 represents a side elevation of the construction shown in Fig. 4.

Referring to the drawings, as shown in Figs. 1 to 3, inclusive, the strap or hanger 1, preferably forged and in a single piece, has the shutter 2, provided with a wide base, pivotally connected therewith by the pintle 3. A pin 4 passes through the parallel members 1' and 1" at the top of the hanger and has the projecting end 4', adapted to engage the aperture 2' in the shutter, a latch 5, pivoted on the shutter, engaging the opening 4" of the pin to secure the block closed. The shutter whose base is made wider than the strap therefore supports the guard 6' and prevents it from breaking, thus avoiding this inconvenience and expense in the usual construction in which a wooden guard is attached to a narrow shutter and has its unsupported ends projecting therefrom. The hanger has secured therein the cheek-piece 6, coacting with the guard 6', and the cheek-piece 7, which coact with the members 9 and 9' in the formation of the pulley-block. The pin 4 passes through the cheek-piece 7, to which it is held

by a key 8 and holds the brace-block 9 in position, the pin and the brace-block acting to stiffen the top of the hanger and prevent the tendency to distortion commonly found in the top of snatch-block hangers. The sheave 10 is supported on the arbor 11, which passes through the cheek-pieces and the hanger members for supporting the same, and the block is supported by the hook 12, which is swiveled in the top of the hanger.

As shown in Figs. 4 and 5, the hanger or strap 13 has the part 13' offset to form with the cheek-piece 14 bearings for the pintle 15 and the shutter 16, through which it passes. The shutter is engaged by the pin 17, which passes through the members 13" and 13'" of the strap, serving to strengthen the head of the hanger as well as to secure the shutter. The pin is held in working position by the nut 17' and is prevented from being wholly withdrawn by a cotter-key 17", which passes through the pin. The hanger also supports the cheek-piece 14', and the arbor 18 is passed through the hanger and the cheek-pieces to support the sheave 19. The hook 20, swiveled in the hanger, supports the block.

Having described my invention, I claim—

1. A pulley-block having an open strap or hanger, a shutter pivoted to said hanger, and a pin passing through the shutter and the hanger members to secure the shutter and brace the hanger, substantially as specified.

2. A pulley-block comprising a hanger having an opening in the side thereof, a shutter having a guard-bearing of greater breadth than said hanger, said shutter being pivoted to said hanger, a cheek-piece supported by said hanger, and a guard coacting therewith and supported by said shutter, substantially as specified.

3. A pulley-block having an open strap or hanger, a closing shutter pivoted to said hanger, a pin passing through the parallel members at the top of the hanger and adapted to engage the shutter, and a key passing through said pin to control the same, substantially as specified.

4. A pulley-block having an open strap or hanger, a closing shutter pivoted to said

hanger, a pin passing through the parallel members at the top of the hanger and adapted to engage the shutter, and a key passing through said pin and fixed with relation to said hanger, substantially as specified.

5 In testimony whereof I have hereunto set my hand, this 28th day of February, A. D.

1903, in the presence of the subscribing witnesses.

JAMES L. DE VOU.
